FLOOR AND CEILING

Ewald Hoyer, Leonberg, near Stuttgart, Germany

Application January 28, 1933, Serial No. 654,065
In Germany January 29, 1932

2 Claims. (Cl. 72—66)

Floors consisting of joists with blocks between them, suitable for use without floor boards and plaster ceilings, have heretofore in most cases been constructed in one or other of two ways. In one case there is a fairly thick concrete layer placed upon the joists and blocks, and this layer, with the joists, affords the structural strength, the blocks being merely fillers. In the second case the blocks are of the full thickness of the floor and have a load bearing function, there being no continuous concrete layer. Floors of this second kind are cheaper to construct, and my invention is concerned with such floors.

According to my invention the blocks between the joists are supported by transverse bearers, which rest upon the joists, and also by bodies of concrete in which the joists are embedded.

Various methods may be adopted for supporting the blocks on the castings of concrete enveloping the joists. The surfaces of the blocks facing the joists may be farther apart at the top than at the bottom, so that a wedge effect is obtained, or the said surfaces may have recesses into which concrete penetrates, to anchor the blocks. In the case of blocks which have passages extending through them, perpendicular to the joists, the poured concrete may flow some distance into these passages before setting, and thus interlock with the blocks.

The invention is illustrated in the annexed drawing, showing examples of construction.

Fig. 1 is a section of part of a floor, taken transversely of the joists, and

Fig. 2 is a section thereof parallel with the joists.

Fig. 3 is a section similar to Fig. 2 but illustrating a modification of a detail.

Fig. 4 is a section similar to Fig. 1, with blocks of a different construction,

Fig. 5 being a cross-section thereof.

Fig. 6 is a perspective view of one of the blocks.

Referring first to the construction shown in Figs. 1 and 2, the floor shown comprises parallel joists *a* of H-section placed at uniform intervals, and bodies *b* which I shall refer to generally as blocks, placed between the joists. The blocks *b* are supported by transverse bearers *c*, which rest upon the bottom flanges of the joists. These bearers *c* may be made of wood, metal, reinforced concrete or any other convenient material.

The blocks *b* may be made of any convenient material, and may be of any convenient length. They have passages extending through them, parallel with the joists.

The bearers *c* form the sole supports of the blocks till the concrete is poured in, and thereafter continue to afford an element of structural strength for bearing the load on the floor. Where the blocks face the joists they have inclined surfaces *b*¹, whereby they are supported upon the concrete. At the top the surfaces *b*¹ are farther apart than at the bottom, the top edges being set back with reference to the edges of the bottom *b*².

Where the blocks placed end to end between parallel joists meet each other, or nearly meet, there are small recesses *g* at the top edges, and these recesses are also filled with concrete *e*. Fig. 3 shows a modification in which these recesses are much deeper than in Fig. 2, extending down to the transverse bearers. The bearers, marked *c*¹ in Fig. 3, are roughly of inverted T-shape, and may consist of concrete.

Fig. 4 shows a modification in which the blocks have passages *f* extending transversely of the direction of the joists. Portions of concrete *e*¹ penetrate into these passages, for interlocking with the blocks.

Fig. 6 shows in perspective a block which has lateral channels *d* and end surfaces *b*¹ as shown in Figs. 1 and 2, but has no passages extending through it.

It will of course be understood that there may be a plaster or like coating on the under surface, for ceiling purposes, and that the top may also be coated or dressed if desired.

What I claim as my invention and desire to secure by Letters Patent of the United States is:—

1. A floor consisting of joists, hollow blocks between said joists, of the full thickness of the floor and having portions projecting under said joists, so that said joists lie in channels substantially closed at the bottom, concrete castings in said channels, wholly enveloping said joists, and transverse bearers supported by said joists and supporting said blocks.

2. A floor consisting of joists, series of hollow blocks between said joists, having recesses in the upper portions of their meeting faces, said blocks being of the full thickness of the floor and having portions projecting under said joists so that said joists lie in channels substantially closed at the bottom, concrete castings in said channels, wholly enveloping said joists, transverse bearers supported by said joists and supporting said blocks, and concrete fillings in said recesses.
